(57) **CLAIM**

The ornamental design for a roof fairing, as shown and described.

DESCRIPTION

FIG. 1 is a top, front, and left side perspective view of a roof fairing according to our new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a top, front, left perspective view of the roof fairing in FIG. 1 showing a right panel in an outer position and a left panel in an inner position;

FIG. 9 is a top, front, right perspective view of the roof fairing in FIG. 1 showing a right panel in a neutral position and a left panel in an inner position;

FIG. 10 is a top, front, left perspective view of the roof fairing in FIG. 1 showing a right panel in an inner position and a left panel in an inner position;

FIG. 11 is a top, front, left perspective view of the roof fairing in FIG. 1 showing a right panel in an outer position and a left panel in a neutral position;

FIG. 12 is a top, front, left perspective view of the roof fairing in FIG. 1 showing a right panel in an inner position and a left panel in a neutral position;

FIG. 13 is a top, front, left perspective view of the roof fairing in FIG. 1 showing a right panel in an outer position and a left panel in an outer position;

FIG. 14 is a top, front, right perspective view of the roof fairing in FIG. 1 showing a right panel in a neutral position and a left panel in an outer position;

FIG. 15 is a top, front, left perspective view of the roof fairing in FIG. 1 showing a right panel in an inner position and a left panel in an outer position;

(Continued)

FIG. 16 is a front elevation view the roof fairing in FIG. 1 showing a right panel in an inner position and a left panel in an outer position;

FIG. 17 is a front elevation view the roof fairing in FIG. 1 showing a right panel in an inner position and a left panel in a neutral position;

FIG. 18 is a front elevation view the roof fairing in FIG. 1 showing a right panel in an inner position and a left panel in an inner position;

FIG. 19 is a front elevation view the roof fairing in FIG. 1 showing a right panel in a neutral position and a left panel in an outer position;

FIG. 20 is a front elevation view the roof fairing in FIG. 1 showing a right panel in an neutral position and a left panel in an outer position;

FIG. 21 is a front elevation view the roof fairing in FIG. 1 showing a right panel in an outer position and a left panel in an outer position;

FIG. 22 is a front elevation view the roof fairing in FIG. 1 showing a right panel in an outer position and a left panel in a neutral position; and,

FIG. 23 is a front elevation view the roof fairing in FIG. 1 showing a right panel in an outer position and a left panel in an inner position.

The broken lines illustrate portions of the roof fairing that form no part of the claimed design.

1 Claim, 13 Drawing Sheets
